Inventor:

Charles T. Raschick

by: J. S. Bradbury

Attorney.

UNITED STATES PATENT OFFICE.

CHARLES T. RASCHICK, OF ST. PAUL, MINNESOTA.

COMBINED PAD-HOLDER AND TICKET-PUNCH.

1,228,046.

Specification of Letters Patent. Patented May 29, 1917.

Application filed May 8, 1916. Serial No. 96,263.

To all whom it may concern:

Be it known that I, CHARLES T. RASCHICK, a citizen of the United States, residing at St. Paul, in the county of Ramsey and State 5 of Minnesota, have invented a new and useful Improvement in Combined Pad-Holders and Ticket-Punches, of which the following is a specification.

This invention relates to combined pad 10 holders and ticket punches especially designed for use in lunch rooms, cafés, and the like, and has for an object to provide a device of this character which is simple, efficient and economical in construction, and 15 which may be conveniently worn or carried about the person of the user, so as to be ready at hand when needed.

Another object of the invention is to provide such a device which permits the punching 20 of a ticket at any desired point and wherein means are provided for the retention of the clippings removed by the cutting action of the punch.

Other and further objects and advantages 25 of the invention will be hereinafter set forth and the novel features thereof defined by the appended claims.

In the drawing,

Figure 1 is a side view of the invention 30 showing a pad of tickets held thereby;

Fig. 2 is a plan of the invention;

Fig. 3 is a section taken on the line X—X of Fig. 2; and

Fig. 4 indicates one form of ticket which 35 may be conveniently carried by the device and which is represented as having been punched along its margin.

Like numerals of reference refer to like 40 parts in the several figures of the drawing.

The illustrated embodiment of this invention comprises a base plate A of any suitable material and configuration, though here shown as being rectangular in shape, the longitudinal side edges of which are bent to 45 form upstanding flanges 2 cut away as at 3 for the greater part of their length to facilitate the easy removal of tickets from a pad thereof, such as B, held upon the base in a manner to be later explained.

In order to permit the proper positioning 50 of the pad upon the base, the latter is provided with an upturned ear 4 adjacent to one of its ends; while soldered or otherwise secured upon the outer face of one of the flanges 2 is an enlarged pocket 5 having an open upper end.

The numeral 6 represents a substantially T-shape plate having adjacent to the end of its stem portion a pair of spaced downwardly projecting ears 7 journaled or pivoted on a rod 8 extending transversely between the flanges 2 and spaced above the base, the plate being of such width as to span the distance between and rest upon the upper edges of the flanges as shown, and one portion of the head of the T completely covering the open upper end of the pocket. A tension spring 9 is positioned about the rod between the ears 7 and is designed to normally maintain the plate in pocket-closing position as shown. At its head edge, the plate is provided with a plurality of spaced pointed teeth 10 which engage the upper surface of the pad of tickets B so as to prevent displacement or loss of the same.

Upon the upper surface of the plate is arranged a spring member which, as shown, includes two arms 11 and 12 extending at right angles to one another and secured at their free ends to the plate; while at the angle portion, the member is provided with an inclined cutting edge or punch 13 of any desired shape which cooperates with the cutting edges of a suitable aperture 14 formed in that portion of the head of the plate 6, which overlies the open end of the pocket 5 so that the clippings removed from a ticket inserted between the punch and the face of the plate are caught and retained thereby. Extending longitudinally of the 50 arm 11 is an elongated slot 15 within which is slidably disposed an abutment or shoulder 16 which may be adjusted therealong and thus properly position the inserted ticket so that it may be punched at the desired 55 point, it being understood that the shoulder limits the inward movement of such ticket as may be desired.

A portion of the base may be stamped therefrom and bent outwardly to form a flange 17 having an aperture 18 by means of which it may be conveniently attached about the person of the user so as to be ready at hand when needed.

At its end remote from the ear 4, the base is provided with stop members in the form of short flanges 19, so that the movement of a pad or pads of tickets such as B is limited in all directions and the ends and edges thereof protected. These limiting means, together with the side flanges and toothed portion of the plate positively position the

tickets upon the base and prevent loss or injury thereto.

In accordance with the patent statutes, I have described the principles of operation 5 of my invention, together with the apparatus which I now consider to represent the best embodiment thereof, but I desire to have it understood that the construction shown is only illustrative, and that the invention 10 can be carried out by other means and applied to uses other than those above set forth within the scope of the following claims.

Having described my invention, what I 15 claim as new and desire to protect by Letters Patent is:—

1. In a device of the character described, in combination, a casing comprising a base having flanges on its longitudinal edges 20 adapted to hold a set of leaves, a receptacle having an open end secured to one of said flanges, a plate pivotally supported above said base for engaging and retaining said leaves thereupon, a portion of said plate 25 covering the open end of said receptacle and being provided with a cutting aperture above the open end of the receptacle, and a punch carried by said plate adapted to co-operate with said cutting aperture.

2. In a device of the character described, 30 in combination, a casing comprising a base having flanges on its longitudinal edges adapted to hold a set of leaves, a receptacle having an open end secured to one of said 35 flanges, a plate journaled between said flanges above said base for engaging and retaining said leaves thereupon, a portion of said plate covering the open end of said receptacle and being provided with a cutting 40 aperture above the open end of the receptacle, and a punch carried by said plate adapted to co-operate with said cutting aperture.

3. In a device of the character described, 45 in combination, a casing comprising a base having flanges on its longitudinal edges adapted to hold a set of leaves, a receptacle having an open end secured to one of said flanges, a plate journaled between said 50 flanges above said base for retaining said leaves thereupon, a portion of said plate covering the open end of said receptacle and being provided with a cutting aperture, a member carried by said plate having a 55 punch adapted to co-operate with said cutting aperture, and an abutment depending from said member for positioning a leaf to be cut between said punch and said plate.

4. In a device of the character described, 60 in combination, a casing comprising a base having flanges on its longitudinal edges adapted to hold a set of leaves, a receptacle having an open end secured to one of said flanges a plate journaled between said 65 flanges above said base for retaining said

leaves thereupon, a portion of said plate covering the open end of said receptacle and being provided with a cutting aperture, a member carried by said plate having a punch adapted to co-operate with said cutting aperture, and a sliding abutment depending from said member for positioning a leaf to be cut between said punch and said plate.

5. In a device of the character described, 70 in combination, a casing comprising a base having flanges on its longitudinal edges adapted to hold said leaves, a stop on said base against which one extremity of said leaves rests, a receptacle having an open upper end secured to one of said flanges, a plate journaled between said flanges above said base and having teeth at one end to engage and retain said leaves upon said base, a portion of said plate covering the open upper end of said receptacle and being provided with a cutting aperture, a member provided with an elongated slot carried by said plate and having a punch adapted to co-operate with said cutting aperture, and an 75 abutment slidably mounted in the slot of said member and depending therefrom for positioning a leaf to be cut between said punch and said plate.

6. In a device of the character described, 80 in combination, a casing comprising a base having flanges on its longitudinal edges and spaced upwardly extending stops between which leaves may be positioned against movement in a plane parallel to that of said 85 base, a pocket receptacle having an open upper end secured to one of said flanges, a plate journaled between said flanges above said base and having teeth at one end to engage and retain said leaves upon said base, a portion of said plate covering the open upper end of said receptacle and being provided with a cutting aperture, a member provided with an elongated slot carried by 90 said plate and having a punch adapted to co-operate with said cutting aperture, and an abutment slidably mounted in the slot of said member and depending therefrom for positioning a leaf to be cut between said punch and said plate.

7. In a device of the character described, 95 in combination, a casing comprising a base having flanges on its longitudinal edges and spaced upwardly extending stops between which leaves may be positioned against movement in a plane parallel to that of said 100 base, a pocket receptacle having an opening therein secured to one of said flanges, a plate journaled between said flanges above said base and having teeth to engage and retain said leaves upon said base, a portion of said plate extending over the opening in said 105 receptacle and being provided with a cutting aperture, a member provided with an elongated slot carried by said plate and hav-

ing a punch adapted to coöperate with said cutting aperture, and an abutment slidably mounted in the slot of said member and depending therefrom for positioning a leaf to be cut between said punch and said plate.

5. In a device of the character described, in combination, a casing comprising a base having flanges on its longitudinal edges adapted to hold a set of leaves, a receptacle 10 having an open end secured to one of said flanges, means journaled above said base for

engaging and retaining said leaves thereupon, said means extending over the open end of said receptacle and having a cutting aperture above the open end of the receptacle, and a punch carried by said engaging means adapted to coöperate with said cutting aperture.

15 In testimony whereof, I have signed my name to this specification.

CHARLES T. RASCHICK.
